UNITED STATES PATENT OFFICE.

ROBERT C. WHITE, OF IRONDALE, ALABAMA.

GRATE SHAKING AND DUMPING MECHANISM.

1,399,911.

Specification of Letters Patent. Patented Dec. 13, 1921.

Application filed November 15, 1920. Serial No. 424,313.

To all whom it may concern:

Be it known that I, ROBERT C. WHITE, a citizen of the United States of America, residing at Irondale, in the county of Jefferson and State of Alabama, have invented certain new and useful Improvements in Grate Shaking and Dumping Mechanism, of which the following is a specification.

My invention relates to a mechanism for dumping and shaking furnace grates.

In Letters Patent No. 1,228,626, issued to me on June 5th, 1917, for a similar invention, I described and claimed means for limiting the short shaking movements of the grate lever, a separate means for limiting the longer dumping movements of the lever, and an adjustable means to engage the lever when in neutral position and shift it to maintain the level of the grates. In the use of my said invention it has developed that the independent action of the leveling means, acting to change the neutral point of the lever, has failed to change the position of the stops and this caused the lever to have an unequal movement to either side from its neutral position. One feature of my present invention is to bring the stops and the leveling appliance all into relation for joint movement so that I am enabled to vary the neutral point to level up the grates and at the same time preserve the equal limited shaking play for the lever in both directions from its neutral position.

A further feature of my invention is to utilize a pair of hinged stops jointly adjustable adapted to co-act with a lug on the shaking lever, one to lock the lever in neutral position, the other to limit its shaking movements, and when both are raised the lever is free for a full dumping movement properly limited by stops on the fulcrum bracket.

A further object is to mount the two hinged stops upon a common adjusting screw so disposed as to enable the adjusting of this screw to vary the neutral point of the lever and level up the grates.

My invention further comprises the novel details of construction and arrangements of

parts, which in their preferred embodiment only are illustrated in the accompanying drawings, in which:—

Figure 1 is a side view of my improved shaker with the locking stop out of operating position and the shaking stop in operating position, the lever standing in neutral position.

Fig. 2 is a plan view of the device with both stops in operative position.

Fig. 3 is a partial vertical cross sectional view taken on the line 3—3 of Fig. 2.

Fig. 4 is a detail cross sectional view taken on the line 4—4 of Fig. 2.

Similar reference numerals refer to similar parts throughout the drawings.

As illustrated in the drawings, I show a bracket 1 adapted for attachment to the boiler front 1^a and having a horizontal projection 2 carrying at its outer end a hollow segmental guide 3, the top wall 4 of which is struck on a curve from the pivot bolt 5 at the center of its lower edge. I mount on the pivot bolt 5 a lever 6 having its upper end disposed to travel in the hollow guide and provided with a laterally extending lug 7 which projects through and travels in an arcuate slot 8 in one side wall of the guide 3. The upper end of the lever is provided with a socket 9 and travels in spaced relationship to the under surface of the curved top wall 4 of the guide. This wall 4 is provided with a slot 10 extending throughout an arc corresponding to the maximum regular movement contemplated for the lever. The overhanging edges of this slot are cut away at the center points to form notches 11 which permit the insertion through the slot at this point only of the lugs 12 near the lower end 14 of the handle which is shaped to fit snugly into the socket 9. The lugs 12 are of such thickness as to travel freely between the top of the lever and the top wall 4 of the frame.

By this arrangement the handle can only be inserted or removed at its neutral position and yet when once inserted will rock freely through the slot 10 for the full length thereof. By being removable only at its

center or neutral position the grates will be left level or the handle will remain connected to the shaker mechanism and thus indicate when the apparatus has not been left in proper operating position.

The lower end 15 of the lever is bifurcated to straddle the shaker bar 16 which is attached to the straps 14 which connect the grate sections for shaking. A pivot bolt 10 17 connects the lever and shaker bar.

Projecting above and to one side of the bracket extension 2 is a raised boss 18 having an oblong hole 19 for a screw 20, having flattened side faces 21, which is adapted 15 to slide through but not to rotate in said hole. Nuts 22 on each side of the boss hold the screw in adjusted position. At its outer end the screw carries a yoke 23 in which a stop 24 for limiting the shaking movements of the grate is pivotally connected by a bolt 25. This stop is provided on its under face with a notch 26 which normally receives the lug 7 on the lever so as, by engagement of the latter with its end walls, 20 to limit the shaking movements of the grates. A lock stop 27 is pivotally connected to the outer side of the limit stop 24 by means of a pivot bolt 28, and this stop 27 has a notch 29 which fits snugly about 25 the lug 7 without allowing it any play.

When the lock stop 27 is in engagement with the lug 7, by adjusting the screw 20 the lug can be shifted to level the grates and it is to be noted that the length of the 30 notches 11 is sufficient to take care of the range of adjustment required in this connection. Due to the fact that both stops 24 and 27 are adjusted together the neutral position of the lug 7 will always be in the center of the notch 26 and thus wherever the leveling 35 adjustment may leave the parts, the lever will travel an equal distance from each side of its neutral point and thus will rock the grates equally to both sides.

40 In operation, assuming the lever to be in neutral position with its socket 9 in line with the notches 11 of the guide frame, to shake the grates the handle 13 is dropped into position through notches 11 and interlocked 45 with the lever, the lock stop 27 is swung up from operating position as in Fig. 1, and the limit stop 24 is riding on the lug 7. The lever is then thrown forward and backward with its strokes limited by the ends of the 50 notch 26 and this movement is imparted through the shaker bar 16 to shake the grates. If it be desired to dump the grates 55 the limit stop 24 is itself swung up to idle position and then the lever can throw the grates the full length of the slot 8 in the guide and dump them. This slot limits the dumping movement so that the grates cannot be turned over. Having completed the 60 dumping, the stops 24 and 27 are thrown

back into engagement with the lug 7 and 65 when the handle is moved to neutral position so that it can be lifted out through the notches 11, the notch 29 in the lock stop will engage the lug 7 on the lever and lock the 70 grates in level position. If it be found that as thus locked the grates are not truly level the nuts 22 are adjusted until the grate is pulled level and this adjustment does not effect the operation of any of the parts here- 75 fore described.

Having thus described my invention, what I claim as new and desire to secure by Letters Patent, is:—

1. In a grate shaking mechanism, a pivoted shaking lever having a projection, a notched stop member movable into position to engage said projection to limit the angular movements of said lever, a second movable stop member movable to engage said projection and hold the lever in neutral position, and a common means to adjust said stop members.

2. In a grate shaking and dumping mechanism, a pivoted shaking lever having a projection, a fulcrum member for the lever with stops to limit its grate dumping movements, a notched stop movable to engage the projection and limit the shaking movements of the grate, a notched stop movable to engage the projection and hold the lever 95 in neutral position, and means to adjustably support said stops, said notched stops being sufficient in length to drop into contact with said projection in all positions of the lever.

3. A grate shaking mechanism comprising a bracket, a shaking lever pivoted on the bracket, a projection on the lever, an adjustable element mounted on the bracket, and two pivoted notched stop members carried by said element and having different sized 100 notches which are adapted to receive said projection and limit the movement of said lever, one notch being adapted by contact with the said projection to limit the lever's movements to that required to shake the 110 grate, and the other notch being relatively elongated to permit of a lever movement sufficient to dump the grate.

4. In a grate shaking mechanism, a shaking lever, a fulcrum therefor, a stop to lock 115 the lever in neutral position, a stop to limit the lever to predetermined shaking movements, and means to adjust said stops together to preserve their relative positions while varying the neutral position of the 120 lever.

5. A grate shaking mechanism comprising a shaking lever, a support therefor, an adjustable member on the support, a pair of pivoted stops carried by said adjustable 125 member and adapted to engage the lever, one stop being adapted to hold the lever in neutral position and the other to limit its

shaking movements, substantially as described.

6. A shaking mechanism in accordance with claim 5, in which the adjustable member is a screw flattened so as to slide but not 5 to turn in the bracket, and set nuts which engage and hold the screw in adjusted positions.

7. A shaker mechanism in accordance with 10 claim 4, in which the stop for holding the lever in neutral position is pivotally mount-

ed on the stop controlling the shaking movements of the lever.

8. A grate shaking mechanism in accordance with claim 4, in which the pivoted 15 stops when swung upwardly will stand in inoperative position.

In testimony whereof I affix my signature.

ROBERT C. WHITE.
